LENA A. RUSSELL, OF CLEVELAND, OHIO.

PRESSER-FOOT-LIFTER ATTACHMENT FOR SEWING MACHINES.

Application filed June 20, 1927. Serial No. 200,123.

This invention has for its object to provide an improved device to be permanently attached to an ordinary sewing machine for darning and other sewing operations, providing means for quickly maintaining the sewing machine presser foot raised, permitting the goods to be freely worked back and forth under the needle and over the feed rack for darning with the usual lock stitch.

Referring to the drawings, Fig. 1 is a fragmentary front view of the sewing machine head, Fig. 2 is an end view thereof, Figs. 3, 4 and 5 are detail views of the attachment, and Fig. 6 is a detail view of another form of attachment bracket.

In the drawings 5 indicates the head of an ordinary sewing machine having a face plate 6 secured by a thumb nut 7, and a presser bar 8 on which is mounted the presser foot 10 by means of a nut 9. The reciprocating needle bar 11 carries a needle 12. The base 13 of the machine has a needle hole plate having a slot in which the feed rack 14' travels with four movements.

The attachment comprises a yoke 15 which is clamped between the presser foot 10 and nut 9. The yoke carries a rod 16 screw threaded at the upper end thereof extending through the ear 18 of a bracket plate 17 having slots 19. The plate 17 is placed against plate 6 and clamped by nut 7. A nut 20 is threaded on rod 16.

When darning operations are desirable, the nut is turned downward lifting rod 16 and presser foot 10, allowing the cloth to be freely moved over the traveling feed rack 14' in any direction.

Another form of rod bracket 17^a shown in Fig. 6 is adapted to be applied to other makes of sewing machines.

The slots 19 in the bracket plate 17 permit the bracket plate to be set at various heights, one or the other of the slots being fitted over the screw which receives the nut 7.

The nut 20 may be screwed down to lift 45 the presser foot to any height desired and retain the same in raised position. When the nut is released or unscrewed to a sufficient extent the presser foot will have its usual action and ordinary sewing can be done.

I claim:

The combination with a sewing machine head and face plate, and presser foot rod, of a bracket clamped against the face plate, a rod having a yoke at its lower end fixed to the lower end of the presser foot rod and extending at its upper end through a hole in the bracket, and an adjustable nut on the said upper end of the rod, resting on the bracket.

In testimony whereof, I do affix my signature.

LENA A. RUSSELL.
